CLAIM

The ornamental design for a ratchet powered wheelchair, as shown and described.

DESCRIPTION

FIG. 1 is a top and front perspective view of a ratchet powered wheelchair showing my new design;
FIG. 2 is a front elevational view thereof;
FIG. 3 is a rear elevational view thereof;
FIG. 4 is a left side elevational view thereof, the right side elevational view being a mirror image of that shown;
FIG. 5 is a top plan view thereof; and,
FIG. 6 is a bottom plan view thereof.

FIG.1.

FIG. 4.

FIG. 2.

FIG. 5.

FIG. 3.

FIG. 6
